[57] CLAIM

The ornamental design for a shoe cupsole, as shown and described.

DESCRIPTION

FIG. 1 is a side elevational view of one side of a shoe cupsole showing our new design;

FIG. 2 is a side elevational view of the other side of the shoe cupsole shown in FIG. 1;

FIG. 3 is a front elevational view of the shoe cupsole shown in FIG. 1;

FIG. 4 is a rear elevational view of the shoe cupsole shown in FIG. 1;

FIG. 5 is a bottom plan view of the shoe cupsole shown in FIG. 1;

FIG. 6 is a partial cross section taken along line 6—6 of FIG. 5;

FIG. 7 is a partial cross section taken along line 7—7 of FIG. 5;

FIG. 8 is a partial cross section taken along line 8—8 of FIG. 5;

FIG. 9 is a partial cross section taken along line 9—9 of FIG. 5;

FIG. 10 is a partial cross section taken along line 10—10 of FIG. 1;

FIG. 11 is a partial cross section taken along line 11—11 of FIG. 1;

FIG. 12 is a partial cross section taken along line 12—12 of FIG. 1;

FIG. 13 is a partial cross section taken along line 13—13 of FIG. 1;

FIG. 14 is a partial cross section taken along line 14—14 of FIG. 1;

FIG. 15 is a partial cross section taken along line 15—15 of FIG. 2;

FIG. 16 is a partial cross section taken along line 16—16 of FIG. 2; and,
FIG. 17 is a partial cross section taken along line 17—17 of FIG. 2.

The broken line showing of a shoe upper in FIGS. 1-4 is for illustrative purposes and forms no part of the claimed design.
